UNITED STATES PATENT OFFICE

HERBERT H. WALTERS, OF SYRACUSE, NEW YORK

BREAKER POINT GRINDER

Application filed January 18, 1932. Serial No. 587,312.

This invention relates to a device for grinding the contact points of electric circuit breakers commonly used in the ignition systems of internal combustion engines as applied more particularly to automobiles and other motor vehicles and is similar in some respects to that shown in my pending application Serial No. 550,483 filed July 13th, 1931 in that it includes a rotary shaft mounted upon a suitable supporting frame and provided with a grinding disk adapted to be inserted between the contact points for grinding the same in parallel relation.

The main object, however, of the present invention is to simplify the construction and at the same time to increase the general efficiency of the device by providing it with means adapted to receive one of the contact points and thereby to hold the grinding disk in proper grinding relation to both of the contact points while the disk is being rotated by hand.

In other words, I have sought to provide a device of this character at a sufficiently low cost so that owners of cars may do their own grinding, if desired, and at the same time to permit the device to be stored in any tool receptacle with which the automobile is usually equipped ready for use any time.

Other objects and uses relating to specific parts of the device will be brought out in the following description.

In the drawing:—

Figure 1 is a perspective view of the entire device ready for use.

Figure 2 is an enlarged sectional view partly broken away taken along line 2—2, Figure 1.

As illustrated, this device comprises a frame —1— having laterally spaced arms —2— and —2'— provided with apertures —3— and —3'— for receiving the opposite ends of a rotary shaft —4—.

One end of the shaft —4— is provided with a hand crank —5— by which the shaft may be turned, the other end being threaded at —4'— and engaged by a suitable nut or bushing —6— which, in turn, is journaled in the adjacent opening —3'—.

One of the arms as —2'— is provided with

an extension —7— having an opening —8— for receiving one of the contact points —a—, the other contact point —a'— being mounted upon the usual movable member —b— which is spring pressed toward the contact point —a—.

A relatively thin grinding disk —9— of carborundum, emery cloth or any other suitable material is clamped to the shaft —4— between the inner end of the nut —6— and a shoulder —10— on the shaft to hold said disk in close proximity but in slightly spaced relation to the inner face of the adjacent arm —2'—.

The disk —9— is of sufficient diameter to extend radially across and beyond the opening —8— in the arm —2— so that when the extension —7— is placed over and upon the adjacent contact point —a—, the adjacent portion of the disk will be interposed between the contiguous faces of both contact points for grinding purposes.

The frame —1— preferably consists of a single piece of rather heavy wire having its intermediate portion bent in the form of a handle —1'— and its opposite ends arranged in parallel spaced relation and preferably flattened to form bearings for the opposite ends of the shaft —4—.

The combined thickness of the extension —7— and disk —9— is somewhat less than the distance between the contact points —a— and —a'— when the latter are fully opened.

The disk —9— is firmly clamped between the shoulder —10— and clamping nut —6— on the shaft —4— to rotate with said shaft, but in case it should be necessary to remove the disk by reason of impairment or other cause, it is simply necessary to remove the clamping nut —6— and then to withdraw the shaft —4— endwise from the arm —2'— sufficiently to allow the disk to be removed and another one replaced after which the shaft with the disk thereon may be restored to its operative position and the disk secured in place by the tightening of the nut —6—.

Operation

When it is desired to use the device for grinding the breaker points, the latter will

be opened by one hand while with the other hand holding the device the extension —7— and adjacent portion of the disk may be inserted between the contiguous faces of the breaker points until the opening —8— registers with the point —a—.

The device is then moved endwise in the direction of the breaker point —a— until the latter enters the opening —8— after which the previously opened contact points are allowed to close upon opposite faces of the interposed portion of the grinding disk —9—.

The shaft —4— with the grinding disk —9— thereon is then rotated by means of the hand crank —5— with the assurance that both faces of the breaker points will be ground in parallel planes.

This operation is continued until the breaker points are properly ground following which they will be opened by hand sufficiently to allow the removal of the extension —7— and disk —9— from between them, it being understood that the entire device will be held in one hand by means of the handle —1'— while the shaft —4— and grinder are being rotated by the other hand and that the removal of the extension —7— and disk —9— from between the points will allow the latter to open and close in the usual manner for circuit breakers of this character.

It will be noted that the device is particularly simple, practical and efficient and may be manufactured with very little cost, but

obviously various changes may be made in the detail construction without departing from the spirit of the invention.

What I claim is:

1. In a breaker point grinder, a supporting frame having an arm provided with an aperture for receiving one of the breaker points, a rotary shaft operable at will journaled in said arm, and a grinding disk secured to the shaft and extended across said aperture in close proximity to said arm and adapted to be interposed between the breaker points during its rotation. 70

10. A breaker point grinder as in claim 1 in which the shaft is provided with a relatively fixed shoulder and a removable shoulder between which the grinding disk is 75 clamped. 80

15. A breaker point grinder comprising a U-shaped frame having its base provided with a handle and its opposite arms provided with apertures, a shaft journaled in said apertures and provided with a hand crank by which it may be rotated, one of said arms being provided with an additional aperture 85 adapted to receive one of the breaker points and a grinding disk secured to the shaft and extended beyond the additional opening 90 adapted to be inserted between the same when the shaft is rotated. 95

In witness whereof I have hereunto set my hand this 17th day of December 1931.

HERBERT H. WALTERS.
